Richard Morse Chapin and Hamlin Taylor Haynes,
Charlotte, N.C., assignors to Paoli Chair Company,
Inc., Paoli, Ind.

Filed Aug. 5, 1974, Ser. No. 495,050

Term of patent 14 years

Int. Cl. D6—01

U.S. Cl. D6—49

Fig. 1

FIG. 1 is a side elevational view of the chair;
FIG. 2 is a back elevational view thereof; and
FIG. 3 is a front elevational view thereof.

The design is characterized by the specific appearance of the chair back as illustrated in FIG. 3.

We claim:

The ornamental design for a rocking chair, as shown and described.
